UNITED STATES PATENT OFFICE.

ELLEN M. OVIATT AND ALEXANDER DEAN, OF DENVER, COLORADO.

APPARATUS FOR DESULFURIZING ORES.

SPECIFICATION forming part of Letters Patent No. 680,171, dated August 6, 1901.

Application filed November 12, 1900. Serial No. 36,171. (No model.)

To all whom it may concern:

Be it known that we, ELLEN M. OVIATT and ALEXANDER DEAN, citizens of the United States, residing in Denver, in the county of

5 Arapahoe and State of Colorado, have invented certain new and useful Improvements in Apparatus for Desulfurizing Ores, of which the following is a full, clear, and exact description, reference being had to the accompanying drawings, forming part of this specification.

Our invention relates to an apparatus for use in extracting sulfur from sulfur-bearing ores, the prime object of the invention being 15 to provide an apparatus in which the major portion of sulfur is removed in gases at the lowest temperature in order that other values that are more susceptible to loss may be preserved.

20 A further object is to provide means whereby the sulfurous gases are delivered from the apparatus immediately upon their release.

A further object is to provide for the release from the ore of the last traces of sulfur 25 by subjecting such ore to intense heat, thus transforming the sulfur into a fixed gas.

Our invention consists in features of novelty hereinafter more particularly described, and set forth in the claims.

30 Figure I is a view of our apparatus, shown partly in perspective and partly in vertical section. Fig. II is a view of the retort-cylinder, screw conveyer, and gas-conveyer, shown partly in elevation and partly in vertical section. Fig. III is a vertical sectional view taken on the line III III, Fig. I. Fig. IV is a vertical sectional view taken on the line IV IV, Fig. I. Fig. V is an enlarged cross-sectional view of the retort-cylinder and the 35 screw conveyer therein. Fig. VI is a vertical sectional view taken on the line VI VI, Fig. IV.

1 designates a furnace-body, within which are a settling-chamber 2 and a trough 3, the 45 trough being located at a greater elevation than the bottom of the settling-chamber and inclined upwardly from one of the end walls of the furnace to the settling-chamber. The interior of the furnace is heated by a flame 50 burning in the trough 3, the flame being produced by the use of any suitable fuel. We

prefer to utilize gas or oil as the fuel consumed and introduce the fuel through a fuel-pipe 4, provided with a nozzle 5, through which the fuel is injected by the use of a blast-pipe 55 suitably applied thereto.

6 designates a retort-cylinder located in the furnace in an inclined position and having its lowermost inner end set into the wall of the furnace-body, as seen in Figs. I and II. The 60 retort-cylinder is provided with an outlet 7, located at the lower end thereof above the trough 3, and at the opposite or upper end the cylinder has applied to it a hopper-chute 8, through which the ore to be treated, previously crushed, is introduced into the cylinder. The outer end of the cylinder 6 is loosely set into the furnace-wall to provide for expansion and contraction of the cylinder due to heating and cooling thereof. The cylinder 70 is centrally supported by saddles 9. (See Fig. I.)

10 designates a hollow conveyer-shaft provided with a conveyer-screw 11 and arranged to be revolved by power applied to a drive-pulley 12 and belt 13 or other suitable means. The inner end of the shaft 10 is mounted in a ball-bearing box 14, (see Fig. II,) so that the shaft may be caused to turn freely and with the least friction. At intervals in the hollow 80 shaft 10 are perforations 10^a. (See Figs. III and V.)

15 designates weighted valves carried by arms 16, pivotally connected to the shaft 10. The valves 15 are adapted to close the perforations 10^a during the period that the shaft is revolving with the perforations uppermost, falling by gravity thereto. As the valves descend in the rotation of the shaft they swing away from the perforations, thereby uncovering 90 said perforations and permitting the exit of steam or hot air forced through the hollow shaft by suitable means.

Fixed to the conveyer-shaft 10 at the locations of the perforations 10^a are blades 17, 95 each having a long end that extends to the edge of the conveyer-screw 11 and a short end that projects beyond and protects the perforations against entrance of ore into the conveyer-shaft. These blades are designed to 100 agitate the ore passing through the retort-cylinder and cause the ore to fall in streams at

the locations of the perforations 10^a, so that the particles of ore may receive the full benefit of the steam or hot air forced into the cylinder through the conveyer-shaft.

5 18 designates an inclined chute located beneath the outlet 7 of the retort-cylinder and by which the ore is directed into the trough as it escapes from the cylinder after passing therethrough.

10 Surmounting the retort-cylinder and leading from the interior thereof are risers 19. We have shown three of these risers; but there may be any other desirable number. The risers lead to a manifold 20, into which the 15 sulfurous gases are conducted as they are evolved from the ore treated in the retort-cylinder. The manifold 20 has connected to it a conveying-pipe 21, that may lead to a suitable receiving-chamber to deliver the sulfurous gases thereto for treatment to obtain the values contained by such gases.

20 22 designates a steam-pipe provided with a jet-nozzle 23, (see Fig. II,) that enters the conveying-pipe 21 and serves as an aspirator 25 to draw the gases into said conveying-pipe. We have shown the steam-pipe 22 extending through the manifold 20; but it is evident that it may be placed in any other desirable position to discharge into the conveying-pipe.

30 24 designates a flue leading from the interior of the furnace above the settling-chamber 2. This flue may lead to the manifold 20 or the chamber into which the conveying-pipe 21 discharges.

35 25 designates a discharge-opening at the bottom of the settling-chamber, said opening being closed by a gate 26.

40 Access to the interior of the furnace is provided through a doorway 27, closed by a door 28. (See Fig. III.)

45 In the practical use of this apparatus the interior of the furnace is first heated by the consumption of fuel injected through the fuel-pipe 4, so that the flame will be produced within the trough 3 and immediately beneath the inner discharge end of the retort-cylinder 6. The ore, previously crushed, is introduced into the retort-cylinder through the hopper 8 and is conveyed therethrough 50 by the screw conveyer operating within the cylinder. As the ore passes through the retort-cylinder it is heated to a sufficient extent to liberate the sulfur therefrom in gases, and the said gases pass from the retort-cylinder through the risers 19 into the manifold 55 20, from which they are conducted into the conveying-pipe 21, under the action of the aspirator-nozzle 23, that enters the conveying-pipe. The gases pass through the conveying-pipe to a suitable receiving-chamber, as stated, for treatment to obtain the values thereof. As the ore is conveyed through the retort-cylinder it is constantly lifted by the blades 17 and falls in front of the perforations 60 10^a and receives the blast of steam or hot air emanating from the conveyer-shaft through said perforations, the particles of

ore being thereby subjected to the steam or hot air to separate them from each other and permit the sulfurous gases to escape under 70 the action of the heat within the retort-cylinder. The major portion of the sulfur contained by the ores is effectually liberated therefrom as the ore is passed through the retort-cylinder and at a temperature preferably not exceeding 400° Fahrenheit, at which temperature sulfur is supposed to be volatile. The remaining trace of sulfur is liberated from the ore after it passes from the retort-cylinder through the discharge-opening 80 7 into the trough 3. As the ore falls from the retort-cylinder into the trough 3 it descends into the flame in said trough, where it is subjected to the intense heat of the flame. The sulfur retained by the ore is freed and 85 becomes a fixed gas, which passes from the interior of the furnace through the flue 24, while the ore is carried into the settling-chamber 2 by the force of the blast emanating from the fuel-pipe nozzle. The ore is removed from the settling-chamber through the discharge-opening 25 upon the removal of the gate 26.

We claim as our invention—

1. In an apparatus of the character described, the combination of a furnace, having a settling-chamber, means for heating the interior of said furnace, a retort-cylinder mounted within said furnace, and discharging in front of the means for heating the interior of the furnace, a conveyer arranged to operate within said retort-cylinder, a manifold located directly over the retort-cylinder, having communication with said retort-cylinder, and means whereby the gases liberated in said retort-cylinder are drawn into and delivered from said manifold, the means for heating the interior of the furnace being adapted to complete the roasting of the ore and drive it into the settling-chamber, substantially as described.

2. In an apparatus of the character described, the combination of a furnace, having a settling-chamber, a retort-cylinder mounted within said furnace and provided with an outlet, a conveyer arranged to operate in said retort-cylinder, and means for heating the interior of said furnace immediately beneath the outlet from said retort-cylinder, the means for heating the interior of the furnace being adapted to complete the roasting of the ore and drive it into the settling-chamber, substantially as described.

3. In an apparatus of the character described, the combination of a furnace, having a settling-chamber, a retort-cylinder mounted in said furnace, a conveyer arranged to operate in said retort-cylinder, a trough located within said furnace beneath the outlet from said retort-cylinder, and means for heating the interior of the furnace within said trough and immediately beneath the outlet from said retort-cylinder, the means for heating the interior of the furnace being

adapted to complete the roasting of the ore and drive it into the settling-chamber, substantially as described.

4. In an apparatus of the class described, 5 the combination of a furnace, having a settling-chamber and trough therein, means for effecting a blast-flame within said trough, and for driving the ore into the settling-chamber, a retort-cylinder having an outlet located above said trough, and a conveyer arranged to operate in said retort-cylinder, substantially as described.

5. In an apparatus of the character described, the combination of a furnace, a retort-cylinder within said furnace, a conveyer having a shaft formed with openings and

mounted in said retort-cylinder, and valves arranged to control said openings, substantially as described.

6. In an apparatus of the character described, 20 the combination of a furnace, a retort-cylinder in said furnace, a conveyer having a hollow perforated shaft and mounted in said retort-cylinder, valves arranged to control said perforations, and blades fixed to 25 said shaft at the locations of the perforations therein, substantially as described.

ELLEN M. OVIATT.
ALEXANDER DEAN.
